GRINDING MACHINE.

Application filed January 4, 1923. Serial No. 610,548.

This invention relates in general to grinding machines and aims to provide a machine of large capacity, which will be automatic in its operation, and capable of turning out 5 large quantities of work.

With these ends in view our invention contemplates the provision of a machine having a plurality of grinding wheels, and also the provision of mechanism for automatically 10 actuating the work carrying tables to subject the work thereon to the action of said wheels, so that when work has been positioned on one table, it will be automatically subjected to the grinding operation while 15 the operator is free to remove and replace the work at the other wheel. The machine is therefore a two station machine, capable of being attended by one operator, who removes a finished piece of work from one 20 table and replaces it by a piece to be finished, while another piece is being operated upon at the other station. By dividing his time alternately between the two stations, the operator is enabled to secure continuous 25 operation of the machine without loss of time, so that large production of the machine results.

Another purpose of the invention is to provide a dresser for each grinding wheel, which dressers are so mounted that they may 30 be moved into operative position to dress the face of the wheel without interfering with the grinding operation of the wheel, which may be simultaneously performed.

Another object is to provide suitable 35 adjustments whereby the dressers may be accurately positioned with respect to their grinding wheels, and whereby the length of the stroke of the work tables may be regulated in accordance with the dimensions of 40 the work to be ground; and also adjustments for accurately positioning the tables relatively to their respective grinding wheels.

Other objects and advantages of this invention should be readily appreciated as the 45 same becomes better understood by reference to the following description, when considered in connection with the accompanying drawings:

Referring to the drawings:

Fig. 1 is a side elevation of a grinding 50 machine embodying our invention;

Fig. 2 is an end elevation thereof, looking 55 toward the left at Fig. 1;

Fig. 3 is a fragmentary plan view of one 60 of the wheel dresser mountings; and

Fig. 4 is an elevation of the structure shown in Fig. 3.

By reference to the drawings it will be observed that the machine comprises a suitable base 3 upon which the various operating mechanisms are mounted. The frame of the machine carried by the base includes a standard 4, the upper portion of which is provided with a pair of aligned bearings 5 in which the grinding wheel shaft 6 is journaled, this shaft being adapted to be driven through a pulley 7 fixed thereon from a belt 8 connected with any suitable source of power. Upon the ends of this shaft there are fixedly mounted the grinding wheel 70 chucks 9 and 11, equipped respectively with the abrasive disks or wheels 12 and 13. These wheels being faced in opposite directions, and continuously rotated, it will be manifest that two grinding stations are provided by the machine. Since the work supports, the mechanism for operating the same, and the wheel dressers are substantially identical in structure and operation at each station, the detailed description and the reference characters employed to designate the parts should be understood as referring to both stations or the machine.

Upon a knee 14 at the end of the base 3 there is adjustably mounted a standard 15, 85 equipped with bearings 16 in which is journaled a rock shaft 17. An upstanding guide 18 fixed on this shaft carries an adjustable post 19, on the upper end of which is adjustably mounted the work table 21. 90 This table comprises the stationary portion 22 and the slideable top 23 upon which the work to be operated upon is secured by suitable holders (not shown). A coil spring 24, connected at one end to a stud 25 projecting laterally from the stationary portion of the 95 table, is connected at its other end with a threaded rod 26 which projects through an eye formed in a bracket 27, clamped by means of a set screw 28 to a lever 29 by 100 which the table top is moved toward and from the grinding wheel. The connection between this lever and the table top by which movements of the lever may be transmitted to the top, may be of any preferred construction, one form being disclosed in Patent #1,337,352, granted April 20th, 1920.

The action of the spring 24 upon the lever 105 yieldingly urges the table top toward the face of the grinding wheel, and the extent of 110

movement of the top toward the wheel is regulated by a micrometer adjustable abutment 31. The tension upon the spring 24 may be regulated by an adjustable nut 32.

5 The table is counter-balanced so as to normally be sustained in substantially upright position by a counterweight 33 fixed to the outer end of the shaft 17.

10 Swinging movements of the table about the rock shaft 17 as a center for the purpose of moving the work across the face of the wheel, are automatically imparted to the table by mechanism which will now be described. At its inner side the table supporting guide 18 is provided with an arm 34, the upper end of which is equipped with a T slot 30 in which is adjustably mounted a laterally projecting stud 35. A link 36 is provided with an open sided slot 37 adapted 15 to receive said stud, whereby the link is connected to the table. The opposite end of the link 36 is connected to a rotatable wheel or crank disc 38 by means of a wrist pin 39, adjustably mounted in a diametral undercut 20 groove 41, formed in the face of the disc 38. It will be obvious that rotation of the disc 38 will, through the link 36, impart an oscillatory movement to the work table, the length of the stroke of which may be regulated by adjusting the position of the wrist pin 39 in the groove 41 so as to vary its 25 radial distance from the center of rotation of the disk, and the position of the work table may be adjusted without varying the 30 stroke by adjusting the position of the stud 35 in the slot 30. The disk 38 is driven through a gear box containing suitable reducing gears from a pulley 42 driven from the source of power by means of a belt 43.

35 40 For the purpose of dressing the faces of the wheels, we mount at the rear of the machine a pair of wheel dressers. Each dresser comprises a tool 44, mounted upon a spindle 45, which is slidably and rotatably 45 supported in an elongated bearing 46. The dresser at the left-hand side of the machine, viewing Fig. 1, is shown in Figs. 3 and 4.

The base of this bearing is grooved as indicated at 47 to slidably engage a supporting guide 48 adjustably carried by a bracket 49, which in turn is bolted to the casing 51 of the gear box. A screw 52 threadingly 50 engages with an eye depending from the base of the bearing 46, whereby this bearing may 55 be adjusted, upon manipulation of the screw, longitudinally of the guide 48 to adjust the dressing tool toward and from the plane of the face of the grinding wheel. The spindle 45 is provided at the top with a longitudinally extending groove 53, adapted to 60 receive a locking pin 54 by which the spindle is held against rotation.

In order that the dressers may be adjusted angularly with respect to the axis of the 65 wheels, thereby rendering it possible to dress

the wheel faces straight, convex, or concave as as may be desired, we have provided an adjustment for each dresser, the left-hand one of which is best shown in Figs. 3 and 4. The bracket 49 is provided, as shown, with 70 an upstanding pivot pin 55 about which the guide 48 is rotatably adjustable. A plurality of slots 56 formed in the guide concentrically with the pivot pin are adapted to receive fastening bolts 57 threaded into 75 tapped sockets in the brackets, by which the guide is locked in adjusted position. Accurate adjustments is affected by manipulation of two adjusting screws 58 threaded in opposed relation through spaced ears 59, 80 projecting upwardly from the bracket and engaging opposite sides of a tail 61 projecting from the guide 48. By loosening the bolts 57 and manipulating the screws 58, the dresser may be adjusted into any desired 85 angular relation with respect to its wheel.

90 In the operation of a machine embodying our invention, and assuming that a piece of work has been completed, the operator lifts the free end of the link 36 out of engagement with the stud 35, thereby disconnecting the table from its driving mechanism. He then presses downwardly upon the lever 29 and swings the table away from the wheel, whereupon the finished work is removed and is replaced by a piece to be operated upon. The table is then swung toward the wheel, and connection is reestablished between the stud 35 and the link 36, whereupon rotation 95 of the disk 38 will oscillate the table back and forth across the face of the wheel. The work during this oscillation of the table is urged toward and into engagement with the face of the wheel by the spring 24, the extent of this movement toward the wheel being limited by the adjustable abutment 31. While this piece of work is being ground, the operator removes a finished piece on the table at the other station of the machine and replaces it by a piece to be operated 100 upon. By performing these operations alternately at the two stations, one piece of work is being continuously operated upon while another is being changed, with the result that the machine is operated continuously, and one operator is enabled to attend two wheels instead of being obliged to wait 105 when a piece is being ground.

110 As these grinding wheels require frequent dressing, particularly when used upon certain kinds of work, these dressing operations may be performed whenever necessary without interfering with the grinding operation of the wheels. The operator simply 115 steps around to the rear of the machine, slides the dresser bar 45 longitudinally in its bearing to dispose the dresser tool 42 in operative relation to the wheel, whereupon, if necessary, the dresser may be adjusted 120 toward the wheel by manipulation of the 125 130

adjusting screw 52, and angled if necessary by means of the screws 58. Movement of the dresser toward and from the center of the wheel by sliding the dresser bar back and forth in its bearing will enable the entire grinding surface of the revolving wheel to be properly dressed.

The construction, operation, and many of the advantages of our invention should be understood from the foregoing without further description, and while we have shown and described a preferred embodiment, obviously the structural details of the machine may be varied within wide limits without exceeding the scope of the invention, as set forth in the following claims.

We claim:

1. In a grinding machine the combination of a pair of grinding wheels, a work table for each wheel, means for yieldably urging said tables toward their respective wheels, adjustable means for limiting the extent of such movement, and counter-balanced means for automatically moving said tables parallel with the grinding faces of said wheels.
2. In a grinding machine the combination of a pair of grinding wheels, an oscillatory work table for each wheel, and means for automatically oscillating said tables relatively to their respective wheels, said means being detachable to render their respective tables inoperative.
3. In a grinding machine the combination of a pair of grinding wheels, a work table for each wheel mounted to oscillate about an axis parallel with the axis of said wheels, means detachably connected with said tables for automatically oscillating the same, and means whereby the length of the oscillatory stroke of each table may be regulated.
4. In a grinding machine the combina-

tion of a pair of grinding wheels, an oscillatory and counter-balanced table for each wheel, means for adjusting each table vertically, and a link for detachably connecting said crank with its respective table, the throw of said crank being adjustable to vary the stroke of said table.

5. In a grinding machine the combination of a base provided with a knee, a rock shaft mounted on each knee, a work table carried by each shaft, a counterweight suspended from each shaft to counter-balance its table, a pair of grinding wheels mounted in proximity to said work tables, and means for automatically oscillating each work table upon its respective rock shaft as an axis and across the face of its respective grinding wheel.

6. In a grinding machine the combination of a pair of grinding wheels, an oscillatory table for each wheel, means detachably connected with said tables for automatically oscillating the same, means whereby the length of the oscillatory stroke of each table may be regulated, and means whereby the position of the path of movement of each table relatively to its wheel may be changed without affecting the length of the stroke thereof.

7. In a grinding machine the combination of a grinding wheel, a table mounted to travel adjacent to the face of said wheel, and means detachably connected with the table for oscillating the same, said means including provision for varying the length of the table stroke and for varying the position of said stroke with respect to said wheel.
